UNITED STATES PATENT OFFICE

WILLIAM J. H. RUSCHMEYER, OF TOLEDO, OHIO

BANK VAULT SAFE

Application filed February 24, 1930. Serial No. 430,711.

This invention relates to bank vault safes, and more particularly to an improved arrangement of doors whereby the entrance to the safe may be securely closed. While the invention has been illustrated applied to a safe, it will be understood that it may also be used in connection with buildings or other structures.

One object of the invention is to provide the safe with inner and outer doors for its entrance so mounted that when closed, the outer doors will be disposed in overlying and shielding relation to the inner doors and thereby make access to the inner doors impossible when the outer doors are shut.

Another object of the invention is to so arrange the doors that inner doors may be hingedly mounted and outer doors slidably mounted, and not only overlie the inner doors when closed, but also bear against the outer face of the wall at opposite sides of the entrance or doorway for an appreciable distance when closed.

Another object of the invention is to provide the doors with securing means having actuating elements adapted to be firmly secured by bars held in place by a combination lock structure and to further permit the securing bars to include explosive receptacles as a safety element in case it is endeavored to remove the bars by application of heat.

Another object of the invention is to so arrange the securing means for the doors that certain of the same will be operative to lock and release the door, where others will constitute deceptive devices.

The invention is illustrated in the accompanying drawings, wherein

Fig. 1 is a view showing a portion of a safe in horizontal section with the doors closed and disclosed in top plan.

Fig. 2 is a view similar to Fig. 1 with the doors open.

Fig. 3 is a vertical sectional view taken substantially along the line 3—3 of Fig. 1.

Fig. 4 is a sectional view taken along the line 4—4 of Fig. 3.

Fig. 5 is a view in elevation showing the doors closed.

Fig. 6 is an enlarged fragmentary sectional view of one of the securing bars.

Fig. 7 is a fragmentary sectional view showing a slightly modified form of locking means for the doors.

Fig. 8 is a sectional view illustrating another modified form of locking means.

Fig. 9 is a sectional view taken along the line 9—9 of Fig. 8.

Fig. 10 is a fragmentary sectional view illustrating a modified form of door construction.

The numeral 1 indicates a portion of a safe or similar structure including a front wall 2 having an entrance 3 formed therein intermediate its width. The side walls 4 project forwardly from the front wall and between the side walls extend upper and lower walls 5 and 6 in which are formed grooves 7 and 8 constituting tracks. These tracks extend the full width of the upper and lower walls and are parallel to the front wall.

In order to close the entrance 3 there has been provided inner doors 9 which are hingedly mounted at opposite sides of the entrance as shown at 10 and adapted to fit snugly within the entrance when closed with their adjoining edge faces overlapping. It should be noted that the contacting edge faces of the doors are stepped as shown in Figs. 1 and 2 in order to prevent a prying instrument from being forced between the closed doors. Portions of the doors project outwardly from the wall when the doors are closed and these projecting portions are also formed with stepped edge faces.

The outer doors 11 are of greater dimensions than the inner doors, and these outer doors may be referred to as safety doors and extend the full height between the upper and lower walls 5 and 6 and have their upper and lower edge faces formed with longitudinally extending ribs engaged in the grooves or tracks 7 and 8. These ribs, indicated by the numeral 12, may be substantially triangular in cross section, as shown in Figs. 3 and 7, or they may be rectangular in shape as shown in Fig. 10, by the numeral 12'. Antifriction balls 13 are provided in order to allow the doors to slide easily and these bearing balls 13

may be retained in place in any desired manner.

In order to secure the doors when closed, there has been provided bars 14 slidably mounted in pockets 15 formed in the inner doors and similar bars 16 slidably mounted in pockets 17 formed in the outer doors. These bars are to be projected outwardly in order to engage in sockets 18 and 19 formed 10 in the upper and lower walls and in order to be so, the inner portions of the bars are cut to form rack teeth with which mesh teeth of pinions 20 and 21 carried by posts 22 and 23. These posts 22 and 23 are rotatably mounted 15 in the doors and at their outer ends are formed with turning heads 24 and 25, through which are formed passages 26 and 27, as shown in Fig. 2. It will thus be seen that the posts may be easily rotated by grasping 20 their turning heads and movement imparted to the securing bars in order to project or retract them.

By referring to Fig. 3 it will be seen that the posts 22 of the inner doors and the 25 posts 23 of the outer doors are disposed in their upper and lower portions and intermediate the heights of the doors are located other posts 28 and 29 which are rotatably mounted and at their outer ends form the 30 turning heads 30 and 31 similar to the heads 24 and 25. These posts 29 are not engaged with securing bars and may be referred to as dummy posts as they are merely intended to give the impression that the doors have upper, 35 lower and intermediate securing means.

Sockets 32 and 33 project from the inner and outer doors in spaced relation to opposite sides of the turning heads of the post carried thereby and these sockets are rigidly 40 fixed to the doors. By this arrangement, securing bars may be passed through the passages formed in the turning heads of the posts with their end portions engaged through the sockets and it will be impossible to rotate 45 the posts and retract the securing bars 14 and 16 until the bars carried by the posts and sockets have been removed.

The securing bars for the posts are indicated in general by the numeral 34 and 35 50 and are similar in construction to those shown in my prior Patent, No. 1,427,551 issued August 29, 1922, and each is constructed as shown in Fig. 6. Referring to this figure, it will be seen that each includes a hollow bar 36 having a head 37 at one end of sufficient diameter to prevent it from passing inwardly through the socket which supports the bar. A glass tube 38 filled with powder 39 extends 55 axially through the bar 36 and about this tube the bar is filled with a chalking substance such as infusorial earth 39' which acts as a shock absorber and prevents danger of explosions in case a high explosive is used instead of powder. This earth also serves to

prevent danger of the powder being damaged by dampness.

Collars 40, which may be referred to as setting rings, fit loosely about the tubular bar and are formed with grooves 41 through 70 which lug 42 projecting from the tubular bar may pass when the rings are properly set. Unless a person knows the proper combination the rings may not be easily set in order to align the grooves 41 and therefore a person not familiar with the combination will find it very difficult to remove the bars. In addition to placing an explosive within the tubular securing bars, the sockets may be similarly loaded as shown at 43 and also, if so desired, 75 the turning posts may be loaded as shown at 44. It will thus be seen that it will be impossible to rotate the posts in order to withdraw the securing bars or rods 14 and 16 when the securing bars for the posts are in place, 80 and if it is attempted to cut through the securing bars by means of an acetylene torch, the heat will cause the powder to explode and seriously injure any one tampering with the 85 safe.

Instead of having each post actuate a single securing bar or rod, it is sometimes desirable to provide additional securing rods and in order to do so each post may carry a number of pinions, as shown at 45 in Fig. 7. These 90 pinions mesh with rack teeth of a series of rods or bars 46 for the reception of which sockets 47 have been provided and when the post is rotated, all of the rods will be projected or retracted according to the direction 100 in which the post is turned.

Instead of providing a series of rods, as shown in Fig. 7, the structures disclosed in Figs. 8 and 9 may be employed. In this construction the securing means consists of a fork having a number of prongs or arms 48 slidably received in slots 49 formed in the door and connected by a cross-bar 50. The cross bar moves in a pocket 51 formed in the door at the inner ends of the slots 49 and a shank 52 extends from the cross bar intermediate its ends into a pocket 53 for engagement by the pinion 54 carried by the turning post. It will thus be seen that by this construction only a single pinion is necessary, but 110 at the same time, a series of securing arms will be projected from the door.

When the safe is to be closed, the inner doors 9 are first shut and secured, after which the securing bars 34 are applied through the 115 sockets and turning heads, and the outer doors are then slid to a closed position. These outer doors when closed completely hide the inner doors, and since they have portions which extend to the front wall 2 of the safe, 120 and bear against outer side edge faces of the extended portions of the inner doors, the inner doors will be shielded from the sides as well as from the front.

After the outer doors have been closed, and 125

the securing bars 35 set in place, it will be impossible to open them until the bars or rods 16 have been again retracted, and as these doors are very thick, access may not be had 5 to the inner doors until the outer doors are opened.

In view of the thickness of the outer doors, they are very heavy, and in order to permit them to be moved, to open or closed position, 10 there have been provided electric motors 55 carrying drums 56 upon which drawing cables 57 are wound. The cables have, at the ends, hooks 58 which may be engaged with the sockets near the outer side edges of the doors, 15 as shown in Fig. 5, in order to move the doors to an open position, or engage with sockets near the inner side edges of the doors, as indicated by dotted lines, when it is desired to close the doors. By rendering the motors in- 20 operative, after closing the doors, it will be practically impossible to open them, even if a burglar should succeed in releasing the fastenings for the doors without becoming injured.

25 What is claimed is:

1. A structure having a wall formed with an entrance intermediate its ends and other walls projecting from the first wall beyond the outer face thereof, tracks being pro- 30 vided between the second mentioned walls and extending across the entrance, inner doors hingedly mounted at opposite sides of the entrance and when closed having portions projecting outwardly and formed with 35 stepped edge faces, means to releasably secure said doors when closed, outer doors slideable along said tracks and having facing edge faces abutting intermediate the width of said entrance when closed, portions of the 40 sliding doors being thickened inwardly to bear against the outer face of the first wall and having stepped inner edge faces abutting the stepped edge faces of the extended portions of the swing doors when the inner 45 and outer doors are closed, portions of the outer doors between the thickened portions being spaced from the inner doors to clear the securing means thereof when the doors are closed, and means to releasably secure 50 the outer doors closed.

2. A structure having a wall formed with an entrance, inner doors hingedly mounted for movement into and out of a closed position, and when closed having portions projecting outwardly from the wall at opposite side edges of the entrance, outer doors slide- 55 ably mounted in front of the wall for move- ment transversely of the wall from open position beyond opposite sides of the en- 60 trance to a closed position, and when closed having portions extending in front of the closed inner doors and meeting in shielding relation to the inner doors, said outer doors having thickened portions contacting with 65 the wall and adapted to bear against side

edge faces of the projecting portions of the inner doors when closed, means to secure the inner doors when closed, and means to secure the outer doors when closed.

3. A structure including a wall formed 70 with an entrance, inner doors movable into closing relation with the entrance and having portions projecting outwardly from the wall when closed, securing means for said doors having actuating means projecting 75 from the outer faces of the doors, locking means for said actuating means disposed externally of said doors, outer doors slidably mounted for movement into and out of a closed position and having portions of re- 80duced thickness extending in front of the inner doors in spaced relation to the actuating means and locking means carried thereby, and meeting in shielding relation to the inner doors when closed, the thicker por- 85 tions of the outer doors extending towards the wall for contacting with the outer face thereof, and adapted to bear against side edge faces of the projecting portions of the inner doors when the outer doors are closed. 90

4. A structure having a wall formed with an entrance, side walls projecting outwardly from the first wall, upper and lower walls projecting outwardly from the first wall between the side walls and formed with 95 grooves extending longitudinally of the first wall in front of the same to form tracks, inner doors hingedly mounted at opposite sides of said entrance and adapted to be swung inwardly into the entrance when 100 closed, portions of the inner doors projecting outwardly beyond the first wall when closed, securing means for the inner doors having actuating elements projecting from the outer faces thereof, outer doors in front of 105 the first wall having their upper and lower edge faces formed with ribs engaged in the track-forming grooves of the upper and lower walls and carrying anti-friction mem- 110 bers to facilitate the sliding of the outer doors, the outer doors when closed having portions of reduced thickness extending across the inner doors in spaced relation to the securing means for the inner doors and contacting with each other in shielding re- 115 lation to the inner doors and securing means therefor and other portions bearing against the side edge faces of the projecting portion of the inner doors when closed, and means to releasably secure the outer doors when 120 closed.

In testimony whereof I affix my signature.
WILLIAM J. H. RUSCHMEYER.
